DEPOSIT BOX

Joseph Albert Towner, Québec, Québec, Canada

Application December 27, 1952, Serial No. 328,178

1 Claim. (Cl. 193—34)

The present invention relates to a deposit box for bank deposits, letter mail or the like and more particularly to a vault or safe having a passageway communicating with the exterior of a bank, a trust company or other like building, whereby the public at large may make deposits before, during or after business hours, that is, twenty-four hours a day including Sundays and holidays.

Deposit boxes of the character described expedite deposits, avoid loss of time for depositors and enable a more even distribution of the work among employees.

The contents of already known deposit boxes of the character described are liable to be damaged by liquid, fire or other elements due to the fact that any malicious person may insert or drop into the passageway foreign materials such as gasoline, matches, water, acids, explosives and the like. As the contents of said deposit boxes are always valuable, damaging or deterioration results in a considerable loss to the bank and to the customers.

Accordingly, the main object of the present invention is the provision of a deposit box of the character described which is provided with means to prevent liquids and other undesirable articles such as acids, water, matches, gasoline, explosives etc. from entering the vault adapted to receive the deposits.

Yet another important object of the present invention is the provision of a deposit box of the character described which is provided with means to prevent unauthorized withdrawal of the contents in the deposit safe or vault.

Still another important object of the present invention is the provision of a deposit box of the character described which will be burglar-proof and fire-proof.

Still another important object of the present invention is the provision of a deposit box which is provided with two chutes, one being adapted to receive small size packages such as deposit slips, mail envelopes and the like, while the other chute is adapted to receive larger size packages such as money bags and the like.

Yet another important object of the present invention is the provision of a deposit box of the kind described which may also be installed in multi-story buildings, on sidewalks or other public places.

The foregoing and other important objects of the present invention will become more apparent during the following disclosure and by referring to the drawings in which:

Figure 1 is an elevation, partly cut away, of a building wall and of the trap door of the deposit box according to the invention;

Figure 2 is a perspective sectional view of the trap door and upper portion of the chute;

Figure 3 is a longitudinal section of the deposit box arrangement according to the invention;

Figure 4 is a plan section of the same;

Figure 5 is a fractional perspective view, partly in section, of the deposit slip chute;

Figure 6 is a section along line 6—6 of Figure 3; and

Figure 7 is a rear face elevation of the trap door.

Referring now more particularly to the drawings in

2

which like reference characters indicate like elements throughout, A indicates an exterior wall of a bank building or the like to which is secured a base plate 2, preferably made of heavy casting, and provided with a slot 3 for deposit slips and a trap door 1 for deposits of larger size such as money bags and the like.

The base plate 2 is preferably provided with an outward rib (not shown) along the upper edge of the slot 3 to protect the latter against rain and to guide the deposit slips into said slot.

The slot 3 is in communication with a shallow chute 4 of rectangular cross-section and extending downwardly at an angle within the building to open at its downward end into a small vault or safe 5 provided with a combination lock door 6.

The trap door 1 is adapted to establish communication between the exterior and a large size chute 7 extending downwardly at an angle within the building and discharging directly into a vault or space 8 provided at its top with a combination lock door 9. The doors 6 and 9 may be opened only by authorized persons.

In order to prevent liquids and other undesirable articles such as matches, rocks, bricks, explosives, acids and the like from reaching the vaults 5 and 8, a vertical well 10 is provided within the concrete structure of the deposit assembly, said well 10 being disposed adjacent the inside face of the building wall A and communicating with the chutes 4 and 7 through transverse slots 11 and 12 made in the bottom of said respective chutes. A receptacle 13 containing sand or the like is positioned at the bottom of the well 10 to receive the undesirable articles. The receptacle 13 may be removed through a door-opening closed by a door 24. The door 24 may be opened only by authorized persons. Instead of the receptacle 13, a sewer pipe may be provided at the bottom of the well 10, preferably connected with the sewer system of the building and having its opening within well 10 preferably covered with a perforated cone. The well 10 is separated from the vaults 5 and 8 by a thick concrete wall 14 so that the undesirable articles may not damage the contents of said vaults by fire or explosion.

The bottom of the portion of the chute 7 upstream of the slot 12 is formed by a metal plate 26 and by a plurality of longitudinally extending spaced parallel rods 15 projecting within the well 10 and terminated by bevelled elongated ends 16 forming one side of the slot 12. The money bags and the like desirable articles will have a minimum width and length to pass smoothly over the slot 12.

The metal bottom 18 of the downstream portion of the large chute 7 is lined with longitudinally extending spaced parallel rods 15' adapted to facilitate the sliding down of the packages received by said chute 7 and the lower pointed end 17 of said rods 15' project slightly from the bottom 18 to provide fingers for preventing retraction of the contents of the vault 8.

Similarly the bottom of chute 4 is constituted by spaced parallel rods 4' forming pointed fingers 4" at the discharge end of said chute.

To make unauthorized withdrawal of the contents of vault 8 practically impossible, an additional safety device is provided in the form of a gate 19 pivoted at 20 to the side walls of chute 7. A rod 21 passing through a tube 22, connects the gate 19 to the trap-door 1 by means of crank pins 19' and 1' respectively, the latter passing through an arcuate slot 7' made in a side wall of chute 7. The connection is such that opening of the trap-door 1 will close the gate 19 and vice versa.

In order that the lower chute 4 may not prevent the undesirable articles inserted into the upper chute 7 from reaching the well 10, said lower chute 4 is disposed adjacent one side wall of the upper chute 7 and well 10

as shown more particularly in Figure 5. Said side wall forms an inclined wall portion 23 overlying the lower chute 4 in order that the undesirable articles may drop down the well 10 without being obstructed by the chute 4.

The trap door 1 consists in a front plate 25 horizontally pivoted at its lower edge to the bottom lining plate 26 and is provided with sector-like side walls 27 to which is rigidly secured a transverse plate 28 extending at an angle with the front plate 25. A flap 29 is pivoted to the lower edge of the plate 28 for closing the passage formed between the plates 25 and 28. Only deposits of a certain predetermined maximum size will be able to pass through said passage.

Liquids and other undesirable small sized articles which may pass through the opening in the trap door but which have dimensions smaller than those of slot 12 will automatically enter the well 10 through the slot 12. Similarly liquids, matches and the like inserted into the small chute 4 but having dimensions smaller than those of slot 11 will drop into the well 10 through the slot 11 and will not be able to reach the vault 5.

Although a deposit box arrangement particularly adapted to be mounted in a bank building has been described, it will be understood that certain modifications may be resorted to: for instance the installation of such a deposit box may be made in a multi-story building in which a trap door 1 and slot 3 may be provided on each floor and which communicates by auxiliary chutes with common chutes 7 and 4. Likewise the small chute 4 could be dispensed with provided that the well 10, which forms an essential part of the invention, be retained.

While a preferred embodiment according to the invention has been illustrated and described it is understood that various modifications may be resorted to without departing from the spirit and scope of the appended claim.

What I claim is:

An article conducting chute comprising an entrance end

and a discharge end, a bottom for said chute consisting of two groups of longitudinally extending parallel spaced rods, means disposed underneath said rods for supporting the same, the rods of one of said groups extending from said entrance end, said last named rods being downwardly inclined and having their lower ends projecting from said supporting means, the rods of the other of said groups being downwardly inclined, having their upper ends spaced from the lower ends of the rods of said one of said groups so as to define a transverse slot in the bottom of said chute, the lower ends of the rods of the other of said groups terminating at said discharge end of said chute and forming fingers projecting beyond said supporting means, further including a trap door pivoted in the entrance end of said chute, said trap door comprising sector-like side walls, diverging transverse walls connecting said side walls, one of said transverse walls extending short of the other of said transverse walls so as to leave an opening, and a flap pivoted on said one transverse wall to close said opening.
